ATTORNEY

UNITED STATES PATENT OFFICE.

HARRY WEARNE, OF RIXHEIM, GERMANY.

DESIGN FOR WALL-PAPER.

SPECIFICATION forming part of Design No. 33,903, dated January 8, 1901.

Application filed December 18, 1900. Serial No. 40,815. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a section of wall-paper embodying the features of my design.

The leading features of my design are the floral scrolls arranged in simulation of the outline of a lyre, between which scrolls a group of flowers and their stems appear in upright position, the flowers being those of the aster and ranunculus variety.

The minor features of the design consist in the separate grouping of the different varie-

ties of flowers, in the arrangement of the stems and leaves which extend below the meeting-points of the scroll, a ribbon-tie confining the stems, and in the floral festoons which drop from opposite sides of the stems.

Having thus described my invention, I claim as new and desire to secure by Letters Patent—

The design for wall-paper as herein shown and described.

In testimony whereof I have signed my name to this specification in the presence of two subscribing witnesses.

HARRY WEARNE.
